(57) **CLAIM**

The ornamental design for an animal feeder, as shown and described.

DESCRIPTION

FIG. 1 is a front, left side and top perspective view of an animal feeder showing the new design;
 FIG. 2 is a front elevation view thereof;
 FIG. 3 is a left side elevation view thereof;
 FIG. 4 is a rear elevation view thereof;
 FIG. 5 is a right side elevation view thereof;
 FIG. 6 is a top plan view thereof;
 FIG. 7 is a bottom plan view thereof; and,
 FIG. 8 is a left elevation sectional view thereof, along the 8-8 plane indicated in FIG. 6.

The portions of the design shown in broken lines show unclaimed subject matter.
